Primary Examiner — John Windmuller*Assistant Examiner* — John R Yeh(74) *Attorney, Agent, or Firm* — Richard John Bartz(57) **CLAIM**

The ornamental design for a combined floor mat and EAS antenna, as shown and described.

DESCRIPTION

FIG. 1 is a top plan view of my design for a combined floor mat and EAS antenna;

FIG. 2 is a front elevational view thereof;

FIG. 3 is a rear elevational view thereof;

FIG. 4 is a bottom plan view thereof;

FIG. 5 is a right side elevational view thereof;

FIG. 6 is a left side elevational view thereof; and,

FIG. 7 is a sectional view taken along line 7-7 of FIG. 4 thereof.

The broken lines in the figures represent the cut line for a sectional view of the combined floor mat and EAS antenna and form no part of the claimed design.

1 Claim, 2 Drawing Sheets(56)
